Patented Apr. 4, 1922.

UNITED STATES PATENT OFFICE.

ARNOLD O. WEISMANN, OF CHICAGO, ILLINOIS.

TRIMMING KNIFE.

1,411,651.

Specification of Letters Patent.

Patented Apr. 4, 1922.

Application filed September 20, 1920. Serial No. 411,536.

To all whom it may concern:

Be it known that I, ARNOLD O. WEISMANN, a citizen of the Republic of Austria, residing at Chicago, in the county of Cook and 5 State of Illinois, have invented certain new and useful Improvements in Trimming Knives, of which the following is a specification.

My invention relates to blade holding devices and is particularly adapted to utilize discarded safety razor blades and to provide a trimming knife in which the blades may be readily renewed or replaced.

The principal objects of my invention are 10 to provide a handle to which the razor blades of a type similar to that used in the Gillette safety razor may be attached to afford a substantial and convenient trimming knife; to attach the blade to the handle in 15 such a manner that the removal and replacement of the blade may be readily and quickly accomplished; to securely clamp the blade on to the handle and brace same so that looseness or shifting of the blade is 20 prevented; to provide a guard for the blade which reinforces the latter and prevents breakage owing to the thin character of the blade; and in general to provide an improved holder for safety razor blades, of 25 simple form, inexpensive construction, and whereby such blades may be readily secured and held in the holder so as to provide a trimming knife which may be subjected to 30 hard usage without danger of breaking the 35 blade.

On the drawings—

Fig. 1 is a side view of a trimming knife formed of my improved holder with a razor blade attached;

40 Fig. 2 an edge view thereof;

Fig. 3 a sectional view on the line 3—3 of Fig. 1; and

Fig. 4 an edge view of the clamping plates which I employ for attaching the razor blade 45 to the handle.

Referring to the drawings the reference numeral 1 indicates a handle which is preferably of wood or similar material, suitably shaped so as to be conveniently grasped for 50 trimming or cutting with the attached blade, and 2 is a tapered metal socket which is fitted on to the end of the handle 1 and secured thereto by the rivet 3. The end of the handle 1 within the socket 2 is slotted or 55 divided as indicated at 4 and at the inner end of the slit is enlarged, as indicated at 5,

to form an arched seat at each side for a purpose which will appear hereinafter.

The outer end of the socket 2 is shaped to 60 form an end opening 6 of narrow width which aligns with the slit 4 in the handle 1 and at each side of the opening there is a lip 7 extending forwardly from the socket. These lips are of corresponding form and arranged in spaced parallel relation and each 65 has a corresponding circular notch 8 in the outer end.

This holder is designed particularly to be 70 used with razor blades of the type used in the Gillette safety razor, such blades being extremely thin and double edged and provided with a perforation 9 near each end. Owing to the thinness of these blades it is 75 impossible to use them in an ordinary blade holder for cutting purposes, as for example, as a shoe maker's knife for cutting leather, rubber, etc., as the strain of a hard cut either bends the blade so that it will not cut on a straight line or breaks the blade. To enable 80 the blade to be used for work of this character and at the same time afford a simple and convenient means for attaching the blade to the handle, I employ a pair of clamping plates 10 and 11 each of which is similarly 85 formed with a corresponding shank 12 for insertion through the opening 6 of the socket 2 and into the slit 4 of the handle, said plates 10 and 11 being of suitable width just beyond the opening 6 to cover the entire width 90 of the razor blade 13 and being correspondingly cut away at opposite sides, as indicated at 14 and 15, so as to expose the forward portion of each edge of the blade. The portions 14 may be cut away for a somewhat 95 longer distance along the edge of the blade and to a little greater depth than the cut away portions 15 to expose a greater portion 1 of the blade for ordinary use, whereas the less amount of cutting away of the plates 10 and 11 at 15 reinforces the cutting edge to a greater extent and enables the portion of the blade exposed at this point to be used for harder service than the portion exposed at the point 14. However, at both sides the plates 10 and 11 are extended outwardly 10 fairly close to the edge of the razor so as to reinforce the latter and prevent bending and breaking thereof, which would occur in cutting hard materials without such reinforcement. The plate 11 at a point distant from 110 the outer end corresponding approximately to the distance of the holes 9 in the razor

blade from the ends thereof has a circular stud 16 riveted, or otherwise secured, on the inner face and of suitable size to fit somewhat closely in either of the holes 9 of the 5 razor blade 13, and the other plate 10 at a corresponding point is provided with aperture 17 to receive the end of the stud 16 and thereby hold the plates 10 and 11 in alignment. The plate 11 also has another stud 10 18 on the inner face spaced from the stud 16 a distance corresponding to the distance between the holes 9 in the razor blade 13, and the plate 10 has a corresponding aperture 19 to receive the stud 18. The stud 18 extends 15 upwardly from the plate 11 so as to project through the opening 19 in the plate 10 when the razor blade is clamped therebetween and at the outer side of the plate 11 is a corresponding stud 20, and these studs 18 and 20 20 when the plates 10 and 11 are inserted in the socket 2 fit into the notches 8 of the lips 7 of the socket to steady or brace the clamping members 10 and 11 and prevent shifting thereof and consequent looseness of the blade 25 13 on the handle in the operation of cutting. The plates 10 and 11 are bowed outwardly intermediate of their ends, as shown in Fig. 4, so that when the shanks 12 thereof are inserted in the socket 2 the exposed portions 30 of said plates 10 and 11 and particularly the outer ends thereof will press firmly against the opposite sides of the blade 13. The shanks 14 of each of the plates 10 and 11 at their inner ends are oppositely arched at 35 21 so as to spring outwardly into the cavities 5 at opposite sides of the lower end of the split 4 when the shanks 12 are fully inserted so as to hold the plates 10 and 11 securely in the fully inserted position in the socket 2. 40 It will be observed that the forward end of the socket 2 is rounded as at 22 and the opposite ends of the opening 6 are located a short distance back of the rounded portions 22, thereby serving to stiffen the forwardly. 45 projecting lips 7 and afford a slight spring or give which insures the lips 7 being held firmly against the outer faces of the plates 10 and 11. In attaching a blade to this holder the 50 plates 10 and 11 are merely withdrawn from the socket 2, a substantial pull being required owing to the engagement of the expanded ends 21 in the slotted opening of the handle 1, and then the razor blade 13 is 55 placed between the plates 10 and 11 with the openings 9 of the blade fitted on the studs 16 and 18. The plate 10 is then pressed down against the top of the razor blade so that the openings 17 and 19 of the plate 10 engages 60 the studs 16 and 18 respectively and the shanks 4 of these plates inserted in the socket 2 until the studs 18 and 20 engage the notches 8 of the lips 7. When so engaged the expanded ends 21 of the shanks 4 engage in the 65 enlarged lower end 5 of the slit 4 and hold

the clamp plates 10 and 11 securely connected to the handle 1.

While I have shown and described my invention in a preferred form, I am aware that various changes and modifications may 70 be made without departing from the principles of my invention, the scope of which is to be determined by the appended claims.

I claim as my invention:

1. In a knife, the combination of a handle 75 having an elongated socket opening extending into the end thereof, a pair of clamping plates adapted to grip and hold a blade therebetween and provided with corresponding extensions adapted to be inserted in the 80 socket opening of the handle, said extensions being provided with laterally expansible portions at their inner ends and the socket being provided with lateral seats at the inner end adapted to be engaged by 85 the expansive portions of the extensions for holding the extensions in the fully inserted position, and a ferrule on the handle having an opening in alignment with the socket opening and engaging the outer faces of the 90 clamping plates adjacent the inner end of the blade so as to press the plates against the blade.

2. In a knife, the combination of a handle having an elongated socket opening in one 95 end, a pair of clamping plates having corresponding extensions adapted to be inserted in the socket opening so as to hold a blade therebetween, said clamping plates being reversely arched from end to end and engaged midway between the ends of the arched portions by the outer end of the socket so as to be flattened against the blade and exert spring tension thereon when the extensions are inserted in the socket open- 100 ing of the handle.

3. In a knife, the combination of a handle having an elongated socket opening in one end, a ferrule on the end of a handle around the elongated opening and provided with 110 an extension at each side of the opening, a pair of clamping plates adapted to hold a blade therebetween and having corresponding portions adapted to be inserted in the opening of a handle, said extensions being 115 arranged to press the clamping plates together when the latter are attached to the handle.

4. In a knife, the combination of a handle having an elongated socket opening in one 120 end thereof, a pair of clamping plates adapted to interlock with and hold a blade therebetween and provided with corresponding portions adapted to be inserted in the opening of the handle, means projecting outwardly from each clamping plate and a projection on the handle at each side of the opening adapted to engage said projecting means of the clamping plates. 125

5. In a knife, the combination of a handle 130

- having an elongated opening in the end, a pair of clamping plates having portions insertable in said opening for attaching the clamping plates to the handle and simultaneously pressing the plates together so as to clamp a blade therebetween, interengaging means on the plates and the blade for holding the plates in the proper relative position and locking the blade therebetween,
- 5 said means being arranged to project at opposite sides of the clamping plates, an extension on the handle at each side of the opening therein having notches in their forward ends engaged by the aforesaid projecting locking means of the clamping plates.
6. In a knife, the combination of a handle having an elongated opening in the end thereof, a pair of clamping plates having corresponding portions insertable in said
- 10 opening for attaching the plates to the handle and pressing the plates together so as to clamp a blade therebetween, a blade interposed between and interlocked with the clamping plates, said clamping plates
- 15 being extended to the outer end of the blade and across the entire width of the inner end of the blade and being correspondingly cut away along the lateral edge from a point between the ends of the blade to the outer end of the blade so as to expose a narrow 30 strip along the edge thereof for a portion only of the length of the latter.
7. In a knife, the combination of a handle having an elongated opening in one end, a pair of reversely arched clamping plates 35 having corresponding extensions inserted in the opening of the handle, a blade interlocked with and clamped between the exposed portions of the plates and having an edge thereof projecting beyond the clamp- 40 ing plates, means projecting at opposite sides of the clamping plates intermediate of the ends of the exposed portions thereof, and a projection on the handle at each side of the opening therein for holding the plates 45 against the interposed blade and having portions at the outer end engaging the projecting means of the clamping plates for bracing same against movement relatively to the handle under cutting pressure.

ARNOLD O. WEISMANN.
